UNITED STATES PATENT OFFICE.

PAUL B. MURPHY, OF NYACK, NEW YORK, ASSIGNOR TO WESTERN ELECTRIC COMPANY, INCORPORATED, OF NEW YORK, N. Y., A CORPORATION OF NEW YORK.

SIGNALING SYSTEM.

Application filed June 30, 1924. Serial No. 723,143.

This invention relates to signaling systems and more particularly to improved methods and means for signaling over transmission lines.

- 5 Under the present telephone practice involving the use of telephone lines inter-connecting different exchanges, several different methods of extending connections are employed, such as, manual to manual, manual to automatic or automatic to automatic connections. In a manual to manual connection, the subscriber in the originating exchange first secures a connection to a toll operator's position in his own exchange, who 10 then extends the connection over a toll line to a distant exchange and rings up the toll operator at such an exchange. The toll operator at this exchange requests of the originating toll operator, the number of the desired line and then proceeds to extend the 15 connection to the desired subscriber. In a manual to automatic connection the toll operator in the originating exchange dials the desired line in the automatic exchange without the aid of the toll operator at a distant exchange and in an automatic to automatic connection, no operators are involved but the calling subscriber merely dials the number of the wanted subscriber and the connection 20 is completed over the toll line between the two exchanges. Connections of these types may extend through a number of manual or automatic exchanges involving the use of several toll lines.
- 25 It is the object of this invention to provide cord circuit and toll line equipments suitable for use in the extension of connections of the above types.
- 30 Another object is to provide means associated with such cord circuits and toll line equipments, whereby any one of the well known types of toll lines may be employed such as, for example, ordinary wire toll lines with or without repeaters, a channel of a carrier telephone installation, a radio telephone connection, composite lines or phantom lines. That is, the nature of the signals used for performing the various functions 35 incidental to the extension of a connection is such that the signals may be transmitted over any toll line the same distance and at the same efficiency as the ordinary voice modulated signals and without in any way curtailing the usefulness of these various 40 types of toll lines.
- 45 To attain these objects according to one feature of the invention, sources of alternating current within the voice range of frequencies are employed for the signals transmitted over the toll lines to accomplish 50 the various switching and supervisory functions. A single frequency is used for transmission in each direction and means is provided at each end of the toll lines for automatically interrupting these frequencies at 55 various rates and transmitting such signals to the receiving end to cause corresponding switching and signaling functions to be performed.
- 60 The nature of the invention will more 65 fully appear from the following specification read in connection with the accompanying drawings in which Fig. 1 shows the connection from a subscriber's line diagrammatically with a toll operator's cord circuit 70 and associated dialing circuit arranged in accordance with this invention located at one manual exchange. By means of this equipment a toll operator may extend connections either to another toll operator located at another manual exchange or to a subscriber reached through an automatic or machine switching exchange. Fig. 2 represents the outgoing end of a special toll line 75 equipment arranged in accordance with the invention, located at the originating exchange, and by means of which voice frequency alternating current signals may be transmitted to and received from the distant exchange over any type of toll line as 80 associated therewith. Fig. 3 represents the incoming end of the special toll line equipment arranged in accordance with this invention, located at a distant exchange, and by means of which voice frequency alternating current signals may be received from or 85 transmitted to the originating exchange. Fig. 4 represents a portion of an automatic exchange by means of which automatically called subscribers' lines may be reached from 90 the above mentioned toll line equipments.
- 95 Referring now to the drawings, traffic over the system shown and arranged in accordance with this invention, may be outlined as follows: If it is assumed that a subscriber at 10 has established a connection as far as to the toll operator's position 100 and the toll operator has inserted the answering plug 12 of the cord circuit shown at 100 into jack 11, and ascertained the number of the 110

desired line, the toll operator will then insert the calling plug 15 of this cord circuit into the jack 210 of the outgoing trunk line equipment 200 associated with the toll line 5 220 leading to the incoming toll line equipment 300 at a distant exchange. The toll operator at 100 then proceeds in either one of two manners to extend the connection:

If the wanted subscriber's number can only 10 be reached through the service of a toll operator such as the one at position 310 at the distant exchange, she proceeds to call this toll operator in the usual manner well known in the art except that alternating currents 15 within the voice range interrupted at a certain rate is used for the necessary signal indications. That is, she causes instrumentalities in the cord circuit and the outgoing toll line equipment 200 to be operated to transmit voice frequency alternating currents of 20 for example, 1000 cycles interrupted at a 20 cycle rate over the toll line 220 to the incoming toll line equipment 300 at the distant exchange, these signals then condition 25 the incoming toll line equipment 300 for a manual connection and are translated by the receiving circuit equipment 350 into indications that will not only call the attention of the toll operator at position 310 to the fact 30 that a connection is desired requiring her co-operation, but will also serve as supervisory signals during the establishment and disestablishment of such a connection as well as when the connection is established.

Similar operations of the system take place 35 if the toll operator at position 310 desires to call the toll operator at position 100 except that in this case instead of sending voice frequency alternating currents of 1000 cycles 40 interrupted at a 20 cycle rate, voice frequency alternating currents at, for example, 700 cycles interrupted at a 20 cycle rate are transmitted over the toll line 220 and translated by the receiving circuit equipment 250 45 at the outgoing toll line equipment 200 into signal indications for the attention of the toll operator at position 100.

On the other hand if the wanted subscriber's line is located in an automatic exchange 50 such as the one diagrammatically disclosed in Fig. 4, the toll operator at position 100 proceeds by the operation of a dialing key to connect the common dialing circuit equipment 150 to the cord circuit shown and 55 by means of instrumentalities associated with this dialing circuit, the cord circuit and the outgoing toll line equipment 200, causes voice frequency alternating currents of, for 60 example, 1000 cycles to be transmitted, in one instance interrupted at a 40 cycle rate while in another instance, that is, in the case of the operations of the dial interrupted at the rate of dialing, the corresponding signals received at the incoming toll line equipment 65 300 first prepare this equipment for

the extension of an automatic connection and are translated by the receiving circuit 350 to cause the automatic exchange equipment shown in Fig. 4 to extend the connection to the wanted subscriber's line as well as to 70 cause the various supervisory signaling indications to be given during the establishment and disestablishment of the connection.

The arrangement of the toll line equipments are such that various signals for the 75 supervision of the connection are transmitted back to the toll operator at position 100 during the progress of the call as well as in the breaking down of the connection. Such signals consist of the voice frequency alternating currents of 700 cycles interrupted at various rates such as at a 40 cycle rate or signal indications consisting of the voice frequency alternating currents of 700 cycles interrupted at the 40 cycle rate in the shape of impulses of 60 per minute, which latter impulses are used when all of the toll lines are 80 busy or signal indications of the voice frequency alternating currents of 700 cycles interrupted at the 40 cycle rate in the shape of impulses of 120 per minute which 85 impulses are used when the called line is busy. Such signals are all translated by the receiving circuit equipment 250 at the outgoing toll line equipment 200 into the proper supervisory signal indications for the operator at the position 100.

It is to be understood that the various frequencies of the alternative current sources mentioned and the rates at which they are 100 interrupted are simply illustrative and that the invention is not limited to the employment of these particular values but that any frequencies within the voice range and rates of interruptions most suitable to particular 105 cases in the practice of the invention, may be selected.

It is believed that the arrangement shown will be more fully understood from the following detailed description of series of calls 110 of the types that may be completed thereby. The first type of connections to be considered will be calls extended on the so-called 115 ring down basis, i. e., from a subscriber 10 to a toll operator's position 100 at the originating exchange to the toll operator attending position 310, at the distant exchange and vice versa. The circuits beyond this point have not been shown as they form no part 120 of this invention and as it is well known and understood in the art how manual connections are attended to by outgoing as well as incoming toll operators no further explanations will be made in this respect. Assuming then that the toll operator at 100 has inserted plug 12 into jack 11 and the operator 125 has ascertained the number of the wanted subscriber's line by the connection of his telephone set to the cord circuit the operation of listening key 32, she proceeds by inserting 130

plug 15 into jack 210 and as a result of this action, relays 24, 23 and 202 are operated as follows: battery, winding of relay 24, winding of relay 23, left hand make-before-break contacts of relay 36, sleeve contacts of plug 15 and jack 210, left hand winding of relay 202 outer right hand armature and back contact of relay 216 to ground. The operation of relay 24 forms no useful function at this time. The operation of relay 23, however, closes a circuit for relay 26 as follows: battery armature and front contact of relay 23, outer right hand armature and back contact of relay 42, winding of relay 26, armature 10 and back contact of relay 30 to ground. It should be noted that a circuit is also closed from the battery at relay 23 through lamp 25 and winding of relay 27 in parallel through armature and back contact of relay 15 26 to a ground at a normal contact of the listening key 32. However, this circuit is prevented from lighting the lamp 25 and operating the relay 27 as relay 27 is slow to operate in comparison with relay 26, so that 20 this circuit is almost immediately broken. The operation of relay 202 closes an energizing circuit for relay 203 from battery, winding of relay 203, right hand armature and front contact of relay 202 to ground. Relay 203 in operating closes a circuit for the busy signal 205 as follows: battery and left hand armature and front contact of relay 203, winding of busy signal 205 to ground operating this signal to indicate to other toll operators that the toll line 220 connected to this equipment is busy. She then proceeds 30 to ring the toll operator at the distant exchange by operating ringing key 34. This causes a 20 cycle alternating current source 35 to be connected to the ring lead and ground to the tip lead of the cord circuit and the outgoing toll line equipment in which a bridged circuit containing retardation coils 206, a condenser 207 and an alternating current relay 208 are located. Relay 208 responds to the 20 cycle current and in operating closes a circuit as follows: battery, winding of relay 209, armature and front contact of relay 208 to ground. Relay 209 40 operates and disconnects the outgoing end of the line from the tip and ring leads to the jack 210 and connects the outgoing end to a source of 1,000 cycle alternating current, interrupted at a 20 cycle rate. This interrupted 45 1,000 cycle current is transmitted over toll line 220 and received at the incoming end by the receiving circuit equipment 350 and is then transmitted through the input transformer 352 to the input circuit of vacuum tube 353 where it is amplified. An anti-resonant circuit 354 connected between the plate circuit of the tube 353 and the grid or input circuit of the vacuum tube 355 makes this latter tube responsive to alternating currents which do not vary greatly from 50 55 60 65 70 75 80 85 90 95 100 105 110 115 120 125 130

1,000 cycles. Vacuum tube 355 acts as a rectifier, causing the polarized relay 356 in its output circuit to operate and release at the rate which corresponds to the rate of interruption of the 1,000 cycle current received; i. e., the armature will vibrate in this instance at the 20 cycle rate causing the relay 357 included in the circuit controlled by this relay 356 to be operated as it is tuned to respond only to alternating currents of this frequency. The operation of relay 357 closes an obvious short-circuit at its armature and front contact to ground for the energizing circuit for relay 358, causing relay 358 to release. The release of relay 358 closes a circuit for relay 302 as follows: battery, left hand winding of relay 302, right hand armature and back contact of relay 303, outer right hand armature and back contact of relay 323, make-before-break contact of relay 358 to ground. Relay 302 operates in this circuit and closes a locking circuit for itself from battery, left hand make-before-break contacts of relay 303, right hand armature and front contact of relay 302, right hand winding of relay 302 to ground and also closes a circuit for busy signals 304 and 305 as follows: battery, left hand armature and front contact of relay 302, windings of busy signals 304 and 305 in parallel to ground. A circuit is also closed by relay 302 from battery, left hand make-before-break contacts of relay 303, right hand armature and front contact of relay 302 through supervisory lamp 306 to ground causing this lamp to light to indicate to the operator at 310 that a connection is desired.

In answer to this signal, the operator at 310 inserts plug 311 into jack 314 and relay 303 is operated over an obvious circuit. The operation of this relay opens at its make-before-break contacts the locking circuit for relay 302 which in releasing causes the supervisory signal 306 to be extinguished. However, the busy signals 304 and 305 are maintained operated by the closing of the left hand armature to the corresponding front contact and battery at relay 303. The operator at 310 now actuates her listening key connecting her telephone set in the usual manner to the cord circuit and receives the details of the call from the operator at 100 who has also by this time actuated her listening key 32 and connected her telephone set to her cord circuit. The operator at 310 then proceeds to extend the connection to the wanted subscriber's line and call the subscriber in accordance with the well established practice in the art of telephony. Conversation between the subscriber at 10 and the called subscriber may then take place.

In case the call extended to the operator at 310 is intended for a subscriber that may be reached through the assistance of an operator at another distant exchange, i. e., if the

operator at 310 is merely employed as a connecting operator for a so-called through connection, it may be necessary to send supervisory signals from the operator at 100 at the originating exchange over the toll lines 220 through the incoming toll line equipment 300 to a cord circuit of the operator at 310 and this may be done by the operation of the ringing key 34 whenever such supervisory signaling is desired. The function of the circuits in this instance is the same as that already described when the key 34 was operated the first time except that when relay 358 is released as a result of the reception 10 of an impulse of 1,000 cycle alternating current interrupted at a 20 cycle rate, the relay 340 is operated in place of relay 302 over a circuit as follows: battery, winding of relay 340, right hand armature and front contact 15 of relay 303, outer right hand armature and back contact of relay 323 to ground at the make-before-break contacts of relay 358. This causes the operation of relay 340 which 20 disconnects the tip and ring leads of the toll line 220 and connects the 20 cycle alternating current source and ground to the tip and ring leads of the switchboard end of the outgoing toll line equipment 300, to the jack 314 to a cord circuit of the operator at 310 causing 25 supervisory indications to be displayed in said cord circuit at 310 as is well known in the art.

In case the incoming operator at 310 at 30 the distant exchange decides to extend a connection to a subscriber that may be attended to by the outgoing operator at 100, i. e., a connection in the opposite direction on the toll line 220, a procedure similar to that described above is followed. The operator at 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 cuit of a second tube 255 responds to alternating currents which do not vary greatly from 700 cycles. The second tube 255 receives the 700 cycle current, acts as a rectifier and causes the relay 256 connected in its 70 plate circuit to operate and release at a rate which responds to the rate of interruptions of the 700 cycles received, i. e., in this instance, at a 20 cycle rate. Relay 257 which is tuned to respond only to 20 cycle current is included in a circuit controlled by the armature of relay 256 and is consequently operated. The operation of relay 257 causes an obvious short-circuit to be established for the energizing circuit for 258 which is thereby released. The release of this relay closes the circuits for relays 217 and 240 as follows: battery, right-hand winding of relay 240, left-hand armature and back contact of relay 202 to ground at 85 the normal make-before-break contacts of relay 258, and from battery, right hand winding of relay 217 to ground at relay 258. Relay 217, in operating, closes a locking circuit for itself from battery, left-hand armature and back contact of relay 203, inner left-hand armature and front contact of relay 217 to ground through the left-hand winding of this relay. The operation of relay 240 closes an obvious circuit for the busy signal 205 and also causes the illumination of lamp 241 from the battery at relay 203 through the left-hand armature and front contact of relay 240. In answering this signal, the operator at 100 inserts plug 15 into jack 210 and relays 24, 23 and 202 are operated but lamp 25 is not lighted, as hereinbefore described. The operation of relay 202 causes the operation of relay 203 which in turn opens the locking circuits for relays 217 and 240 thereby releasing these relays and extinguishing lamp 241 but the circuit for the busy signal 205 is maintained from the battery supplied at the left-hand armature and front contact of relay 203. The operator at 100 now actuates her listening key 32 connecting her telephone set in the usual manner to the cord circuit and receives the details of the call from the operator at 310 who has also by this time actuated her listening key corresponding to key 32 and connected her telephone set to her cord circuit. The operator at 100 then proceeds to extend the connection to the wanted subscriber's line and calls the subscriber in accordance with the well estab-

lished practice in the art of telephony. Conversation between the subscriber at the distant exchange and the subscriber at 10 may now take place.

5 In case the call extended to the operator at 100 is intended for a subscriber that may be reached through the assistance of an operator at another exchange in this direction, i. e., if the operator at 100 is merely employed as a connecting operator for a through-connection, it may be necessary to send supervisory signals from the operator at 310 at the distant exchange over the toll line 220 through the outgoing toll line equipment 200 to the cord circuit of the operator at 100. This may be done by the operator at 310 actuating her ringing key whenever such supervisory signaling is desired. The function of the circuits in this instance is 10 the same as that already described when this ringing key was first operated except that when relay 258 is released as a result of the reception of impulses of 700 cycles alternating current interrupted at a 20 cycle rate, the relay 213 is operated in place of relay 240 over a circuit as follows: battery, winding of relay 213, left-hand armature and front contact of relay 202 to ground at the make-before-break contacts of relay 258. This 15 causes the operation of relay 213 which disconnects the tip of ring leads of the toll line 220 and connects the 20 cycle alternating current source and ground to the tip and ring contacts of the jack 210 and plug 15 to the cord circuit of the operator at 100 causing supervisory indications to be displayed thereat as is well known in the art. That is relay 30 is operated causing lamp 25 to light.

20 These various connections may be released when the conversations cease by merely removing the plugs and the various relays will consequently return to normal positions as is well known in the manual telephone art.

The second type of connections to be considered is a call extended on the so-called automatic basis, i. e. from a subscriber at 10 through the toll operator's position at 100 at the originating exchange over the same toll line 220 to the incoming toll line equipment 300 which will, in this instance, be prepared to extend the call through the automatic equipment such as is shown in Fig. 25 4 and through the associated switches to a subscriber such as 410. As the automatic exchange equipment does not form any part of this invention, only a small portion has been shown to sufficiently illustrate how it is 30 affected by and how it reacts upon the toll line equipments in accordance with this invention. In fact any well known type of automatic equipment may be used as long as the proper signal indications may be sent 35 or received to perform the proper functions

in response to dialing and supervisory signal indications through the toll line equipments.

Assuming then, as hereinbefore, in connection with calls extended on the ring-down basis that the toll operator at 100 has inserted the plug 15 into the jack 210 and relays 202 and 203, signal 205, relays 23, 24 and 26 have all been operated and that supervisory lamp 25 is not lighted due to the combination of the slow releasing and slow operating relays 26 and 27, as hereinbefore described. The toll operator at 100 will in this instance, instead of operating the ringing key 34, operate the dialing key 35. The operation of this key closes an obvious 70 circuit for relays 36 and 37. The operation of relay 36 closes an obvious circuit for relay 42 which in operating closes, at its inner right hand armature and make-before-break contacts, a circuit to ground for lamp 80 25 and opens at its outer left hand armature and make-before-break contacts, the circuit for relays 23 and 24 and extends at the outer armature and front contact the sleeve circuit to the marginal relay 152 associated 85 with the dialing circuit. Relay 152 operates in this circuit and causes a circuit for lamp 25 to be closed as follows: battery, left hand armature and back contact of relay 153, inner right hand armature and front contact 90 of relay 152, lead 43, inner left hand armature and front contact of relay 36, lamp 25 to ground at the make-before-break contacts of relay 42. However, this circuit is merely momentary and lamp 25 is not lighted or at 95 least not lighted long enough to be noticed for reasons as hereinafter described. Relay 37 in energizing, disconnects at its upper and inner lower armature, the incoming end of the tip and ring leads of the cord circuit 100 and extends the outgoing ends of the tip and ring leads to leads 40 and 41 respectively, which are connected to ground and battery at the armatures of relay 151 associated with 105 the dialing circuit.

An impulse from this battery and ground is therefore now sent out over the line to the outgoing toll line equipment 200 and causes the operation of the relay 212, over a circuit 110 that may be traced as follows: battery, inner left hand armature and back contact of relay 151, lead 41, inner lower armature and front contact of relay 37, ring contacts of plug 15 and jack 210, lower armature and back contact of relay 213, left hand armature 115 and back contact of relay 214, one section of retardation coil 215, left hand armature and back contact of relay 216, winding of relay 212, left hand section of retardation coil 215, upper armature and back contact of relay 213, tip contacts of jack 210 and plug 15, upper armature and front contact of relay 37, lead 40, middle left hand armature and back contact of relay 151 to ground. The operation 120 of relay 212 causes the operation of re- 125

130

lay 216 over an obvious circuit and relay 216 closes a locking circuit for itself through its inner right hand armature and front contact through the right hand armature and back contact of relay 218 to ground. The operation of relay 216 also by the operation of its outer right hand armature closes a locking circuit for relay 203 as follows: battery, winding of relay 203, inner right hand armature and front contact of relay 203, outer right hand armature and front contact of relay 216 to ground. The operation of this outer right hand armature of relay 216 also removes the short-circuiting ground for the right hand winding of relay 202 causing the resistance in the sleeve circuit to increase sufficiently to cause relay 152 to release and open the circuit for lamp 25 at its inner right hand armature and front contact thereby preventing the lamp from becoming illuminated i. e., the above functions are almost instantaneous and therefore too rapid for the lamp to respond to the circuit hereinbefore described. Relay 216 also opens the bridge across the line for relay 212 causing it to release.

The battery and ground that are connected to the line at relay 151 are disconnected after a short period as the slow to operate relay 151 operates from battery, winding of relay 151, lower armature and front contact of relay 37 to ground. The period of release is determined by the slow action of relay 151. As soon as relay 151 operates a 1,000 cycle current source interrupted at a 40 cycle rate is connected to leads 40 and 41 and an impulse therefrom is transmitted to the outgoing toll line equipment over the toll line 220 to the incoming toll line equipment 300 to cause various operations as hereinbefore described to take place. The complete circuit for this impulse may be traced as follows: from the source of 1,000 cycle current interrupted at 40 through the armatures and front contacts of relay 154, inner and middle left hand armatures and front contacts of relay 151, leads 40 and 41, upper and inner lower armatures and front contacts of relay 37, tip and ring contacts of plug 15 and jack 210, upper and lower armatures and back contacts of relay 213, upper and lower inner armatures and back contacts of relays 209 and 222, tip and ring leads of toll lines 220 through the input transformer 352 of the receiving circuit equipment 350 which acts in a manner as hereinbefore described to cause the operation of relay 360 which short circuits the energizing circuit for relay 361 causing it to release and connect a ground to a circuit for the energization of relay 322. This circuit for relay 322 may be traced as follows: battery, winding of relay 322, inner right hand armature and back contact of relay 323 to ground at relay 361. The operation of relay 322 connects battery to the

winding of relay 303 causing this relay to operate as follows: battery, inner right hand armature and front contact of relay 322, winding of relay 303 to ground. The operation of relay 303 causes the operation of signals 304 and 305 from battery supplied at the left hand armature and front contact of this relay over an obvious circuit. The operation of relay 322 also closes a circuit at its left hand armature and front contact for relay 323 in series with itself but this relay does not operate until the ground at 361 has been removed in which case relay 323 operates and relay 322 and 323 are then held up over the following circuit: battery, winding of relay 322, winding of relay 323, left hand armature and front contact of relay 322, armature and back contact of relay 324 to ground. The operation of relay 322 also closes at its outer right hand armature and back contact a circuit from ground at the make-before-break contacts of relay 362 to the automatic exchange equipment for the conditioning of this equipment for extension of a call as follows: battery to the slow-to-release relay 406, winding of this relay, armature and back contact of relay 407, lead 450, outer left hand armature and back contact of relay 325, outer right hand armature and front contact of relay 322 to ground at the make-before-break contacts of relay 362. This causes the operation of relay 406 which in turn causes the slow-to-release relay 408 to operate over an obvious circuit and this relay establishes an obvious energizing circuit for relay 411. At its inner right hand armature, relay 411 establishes a circuit for relay 407 which may be traced from battery, winding of relay 407, conductors 451 and 462 to ground over the front contact and inner right hand armature of relay 411. Relay 407 in attracting its armature opens the original energizing circuit for relay 406 which relay thereupon releases, removing the original ground from the winding of relay 408 which, however, now remains operated in a circuit extending from battery through the winding of relay 408, armature and front contact of relay 407 to ground over lead 450, outer left hand armature and back contact of relay 325, outer right hand armature and front contact of relay 322 to ground at the make-before-break contacts of relay 362. At its outer left hand armature, relay 411 prepares a circuit for relay 414 and at its inner left hand armature prepares a circuit for relays 422 and 416. At its outer right hand armature, relay 411 prepares a circuit causing the start magnet 412 to operate. This circuit extends from battery through winding of magnet 412, outer right hand armature and back contact of relay 414, armature and back contact of relay 416 to ground at outer right hand armature and front contact of relay 411. Magnet 412 causes the ro-

tary magnet 418 to operate in an obvious circuit. The rotary magnet 418 in operating causes the line switch F to start hunting for an idle district sender in a manner well known in the art.

When an idle district switch such as is diagrammatically indicated at G is reached, the idle condition thereof being designated by the presence of battery on the test terminal 10 thereof, relay 422 operates in a circuit extending from battery, contacts of sequence switch spring 440, armature and back contact of relay 425, terminal 420 and wiper 421 of line switch F, front contact and inner left 15 hand armature of relay 411, both windings of relay 422 to ground through the winding of relay 416. Relay 422 in attracting its armature short-circuits its own right hand winding thereby reducing the resistance in 20 the circuit just traced, sufficiently to permit marginal relay 416 to operate in series with relay 422. Relay 416 upon energizing causes cut-off relay 414 to energize in a circuit extending from battery winding of cut-off relay 414, front contact and armature of relay 25 416 to ground at the outer right hand armature and front contact of relay 411. Relay 414 in attracting its outer right hand armature opens the energizing circuit for magnet 30 412 whereupon this magnet restores, causing the rotary magnet 418 to release. At its inner right hand armature relay 414 prepares a circuit for relay 427 for supervisory purposes which will hereinafter appear. In attracting its outer left hand armature, relay 35 414 locks up under the control of relay 411, and at its two inner armatures 423 and 424, closes through the tip and ring leads to corresponding terminals of switch F for purposes hereinafter to be set forth. At its inner left hand armature, relay 414 closes an energizing circuit for relay 425 from battery, winding of relay 425, terminal 475 and wiper 441 of line switch F to ground at this 40 inner left hand armature and front contact of relay 414. Relay 425 in attracting its armature removes battery from the test terminal 420 of line switch F, whereupon relays 416 and 422 release, the former opening the 45 original energizing circuit for relay 414 which, however, remains locked up as hereinbefore described.

The operation of the control relay 425 of the selected district switch cause an idle 50 sender to be selected in the well known manner whereupon relay 500 operates causing relay 501 to operate through intermediary relays (not shown) to cause a dialing signal to be given to the operator at 100 in the following manner. Relay 501 in operating places a ground on the tip conductor of the line switch F. This ground causes relay 427 to operate in a circuit extending from battery through the winding of relay 427, inner right hand armature and back contact

of relay 428, contacts 423 of relay 414, wiper 498 and contact 431 of switch F, lower left hand contacts of sequence switch spring 480 (1+16), upper right hand contacts of said spring (2 $\frac{3}{4}$ +10) to ground at 70 the contacts of relay 301. Relay 427 in operating causes the ground at relay 411 to be connected to lead 451 which causes the operation of relay 326 as follows: battery, winding of relay 326, lead 451, armature and front contact of relay 427 inner right hand armature and front contact of relay 411 to ground. The operation of relay 326 causes the operation of relay 362 from battery, winding of relay 362, right hand armature and back contact of relay 327, right hand armature and front contact of relay 326 to ground. The operation of relay 362 removes the ground from the lead 450 and connects this lead to the receiving circuit equipment 85 350 to condition it for the reception of dialing impulses.

On the other hand, relay 326 also connects the 700 cycle alternating current source interrupted at a 40 cycle rate to the toll line 220, the outgoing toll line equipment 200 and the cord circuit at 100 to cause the lamp 25 to become illuminative to indicate to the operator at 100 that the dialing may begin. This signal from the 700 cycle current interrupted at the 40 cycle rate is received at the receiving circuit equipment 250 over the following circuit: from the 700 cycle source interrupted at the 40 cycle rate through the left hand armatures and front contacts of relay 326, upper and lower armatures and back contacts of relay 220, left hand armatures and back contacts of relay 218 through the primary winding of input transformer 252. This impulse is effective through the receiving equipment 250 in the manner as hereinbefore described to cause the operation of relay 260 which in turn causes the short-circuiting of the energizing circuit for relay 261. Relay 261 in releasing applies a short-circuiting ground for the left hand winding of relay 202 and thereby causes the resistance in the sleeve circuit to be decreased. The marginal relay 152 is consequently operated as hereinbefore described to connect battery from the left hand armature of relay 153 through the lamp 25 causing it to light as hereinbefore stated as a signal to the operator at 100 that the dialing operations may begin.

Current from the 1000 cycle source in the dialing circuit 150 is now in position to be connected to the receiving circuit 350 as a pulsing current. When, therefore, the operator at 100 operates the dial 155 in accordance with the number of the desired line, ground is connected to the winding of relay 158 from the off-normal contact 156 of the dial 155, causing the relay 158 to operate over an obvious circuit. The operation of 120 130

relay 158 causes the operation of relay 153 over an obvious circuit. Relay 153 in operating provides a locking circuit for itself from battery, right-hand armature and front contact of relay 152 to ground at the outer right-hand armature and front contact of relay 152. The operation of relay 153 also at its left-hand armature and back contact removes battery from the circuit for lamp 25 which is thereby extinguished. It should be noted that the lamp 25 remains extinguished during the entire dialing period due to the backing up relay 153. The operation of relay 158 connects one side of the circuit from the 1000 cycle source to the lead 41 at its right-hand armature and back contact. The pulsing contacts 157 of the dial open for each pulse during the return movement of the dial to normal and thereby cause the relay 159 to release over an obvious circuit and connect the other lead from the 1000 cycle source to lead 42. In this manner pulses are transmitted to the distant end over the outgoing toll line equipment 200 and the toll line 220 into the receiving circuit 350. Each pulse transmitted is equal in time to the open period of the pulse contacts 157 of the dial. When, therefore, the 1000 cycle pulses are received over the line from the outgoing end they are transmitted through the input transformer 352 to relay 356 as hereinbefore described and cause this relay to operate and release at a rate corresponding to the rate of interruptions of the 1000 cycle current by the operation of relay 159, thus disconnecting the ground at its armature from leads 363 and 450 to cause selecting operations to be performed by the automatic exchange equipment shown in Fig. 4. That is relay 500 is caused to respond to the impulses over a circuit as follows: battery, winding of pulsing relay 500, lower right-hand contact of sequence switch spring 493 (3+10½), upper left-hand contact of this sequence switch spring (1+16), contact 432 and ring wiper 445 of line switch F, contacts 424 of relay 414, back contact and outer right-hand armature of relay 428, armature and front contact of relay 407, lead 450, outer left hand armature and back contact of relay 325, outer right hand armature and front contact of relay 322, armature and front contact of relay 362, conductor 363 to ground at the armature of relay 356. When ground is removed from relay 356 in accordance with the interruptions of the dial contact, the ground is also removed from the relay 408. However, this relay remains operated during the dialing period owing to its slow releasing characteristics.

To turn now to the operation of the automatic exchange equipment when all the pulses are registered in the sender, ground is removed from the tip lead at relay 501,

thereby causing relay 427 to release which in turn opens the circuit to ground over lead 451, for relay 326. The release of relay 326 opens, at its right-hand armature and front contact, the circuit for relay 362 which thereby is released causing the dialing lead to be broken at its armature and front contact but substituting therefor the ground at its make-before-break contact to lead 450 to maintain the sender relay 500 energized for the time being. Relay 326 also, in releasing, removes the 700 cycle source interrupted at the 40 cycle rate from the toll line 220 causing relay 261 in the receiving circuit 250 to become energized to remove the short-circuiting ground from the right-hand winding relay 202. This increases the resistance in the sleeve circuit and causes the marginal relay 152 to release. The release of relay 152 in turn opens the locking circuit for relay 153 which is also released to prepare the circuit for the subsequent lighting of lamp 25 as hereinafter described.

When the wanted subscriber's line at 410 is reached a ground is connected at the contact 429 from sequence switch contact 485 to wiper 238 of the line finder switch F, whereupon relay 428 is operated in a circuit which may be traced from battery, winding of relay 428, contacts 437, contacts 439 of relay 414, wiper 438 and terminal 429, contacts 485 to ground. Relay 428 locks through its contacts 447 to ground under control of relay 414. At its inner right-hand armature, relay 428 disconnects relay 427 from the tip lead and at its inner left-hand armature and front contact, connects relay 427 to the wiper 438 of the line finder switch F to ground at 285. At its outer left-hand armature, relay 428 establishes a circuit for relay 327 which may be traced from battery right-hand winding of relay 327, lead 452, outer left-hand armature and front contact of relay 428, conductors 451 and 462, inner right-hand armature and front contact of relay 411 to ground. Relay 327 establishes a locking circuit for itself from battery through its left-hand winding and left-hand armature and front contact, armature and back contact of relay 324 to ground. Relay 327 also breaks permanently at its right-hand armature and back contact the circuit for relay 362 so that this relay cannot be again energized upon the subsequent energization of relay 326 as hereinafter described. The ground from relay 411 also causes the operation of relay 330 as follows: battery, winding of relay 330, outer lower make-before-break contact of relay 330 to lead 452 to ground at 411. Relay 330 locks up over its lower armature and front contact through lead 453 as it should be noted that this lead also received ground from the inner armature and front contact of relay 411 over lead 462. The operation

of relay 330 performs no useful function at this time. The ground on lead 453 also causes the operation of relay 331 from battery, winding of relay 331 to ground on conductor 453. The operation of relay 331 connects the 1000 cycle source, interrupted at a 40 cycle rate, to the armatures of relay 332 causing a short impulse to be sent out on the tip and ring leads but this impulse is not used on this type of connection and is therefore of no significance. The use in another type of connection will be described later. Relay 332 which is slow to release determines the length of this impulse and is released by the operation of the lower armature and back contact of relay 331.

If the wanted subscriber's line is idle, the ground connected at 429 now due to the operation of relay 428 causes the operation of relay 427 over the following circuit: battery, winding of relay 427, inner left-hand armature and front contact of relay 428, contacts 239 of relay 414 wiper 438 contact 439 to ground at 285. The energization of relay 427 again connects lead 451 to ground causing the operation of relay 326. Relay 326, in operating, again connects the 1000 cycle current source, interrupted at the 40 cycle rate, to the toll line 220. The receiving circuit corresponding to this impulse again causes the release of relay 261 which applies a short-circuiting ground to the right-hand winding of relay 202. It should be remembered that relay 153 is at this time released so that when relay 152 now responds, due to the decrease in resistance of the sleeve a circuit for lamp 325 is completed from battery at relay 153, and this lamp is therefore lighted to indicate to the operator at 100 that the called subscriber is idle and that ringing operations may begin.

When therefore all the digits corresponding to the number of the desired line have been dialed, the operator at 100 may release the dialing key 35 and thereby release relays 36 and 37 but leaves relay 42 energized for the time being. The release of relay 37 disconnects the dialing circuit 150 from the operator's cord circuit. The release of relay 36 causes the release of relay 152 and also breaks the energizing circuit for relay 42, but this relay, being slow in releasing, is provided with a holding circuit from the armature and front contact of relay 24 which operates in series with marginal relay 23 over the sleeve circuit as soon as relay 36 is deenergized and lamp 25 is, therefore, maintained energized as it receives battery from the armature and front contact of relay 23.

As the operator at 100 is now connected through the automatic equipment, to the wanted subscriber's line, she may signal the subscriber by the operation of key 34 and the circuits function in the same manner as

described in connection with the calls extended on the ringdown basis, except that the release of the relay 358 in response to the transmission of a current impulse of 1,000 cycles interrupted at the 20 cycle rate causes the operation of relay 499 in the automatic equipment over a circuit as follows: battery, winding of relay 499, sequence switch contacts 494, terminal 496, wiper 497, right hand armature and front contact of relay 471, lead 454, outer right hand armature and front contact of relay 323 to ground at the make-before-break contact of relay 358. The operation of relay 499 causes the application of ringing current from the source 492 over the established connection to actuate the wanted subscriber's bell.

When the called subscriber answers in response to the ringing signal by removing his receiver from the switchhook, ground is removed from the contact 485 at the switch F, thereby opening the circuit for relay 427. Relay 427 in releasing, opens the circuit for relay 326 causing lamp 25 at the operator's position at 100 to be extinguished by the release of the marginal relay 23 as hereinbefore described to indicate to the operator that the subscriber has answered. Conversation may now begin between the subscriber at 10 and the subscriber at 410.

At the termination of the conversation, the subscriber at 410 upon replacing the receiver on the switchhook again causes ground to be placed on the terminal 429 of switch F from contact 485, thereby causing the energization of relay 427. Relay 427, in operating, causes ground from relay 411 to be connected to lead 451 causing the re-energization of relay 326 and the consequent application of current to the toll line from the 700 cycle source interrupted at the 40 cycle rate. This, in turn, as hereinbefore described, causes the lighting of lamp 25 by the energization of relay 23.

The illumination of lamp 25 at this time serves as a disconnect signal to the operator at 100 and she proceeds to take down the connection by withdrawing plug 15 from jack 210. As a result of this action, relays 24, 23 and 202 are immediately released. The release of relay 24 causes the release of relay 42 and the extinguishing of lamp 25. The release of relay 202 causes a short signal from the 1000 cycle source, interrupted at the 40 cycle rate, to be sent to the incoming toll line equipment 300 as follows, i. e., a circuit is closed for relay 224 from battery, winding of relay 224, outer right-hand armature and front contact of relay 203, right-hand armature and back contact of relay 202 to ground. The operation of relay 224 causes current from the 1000 cycle source, interrupted at the 40 cycle rate, to be connected to the left-hand armatures and back contacts of relay 218 to the toll line

220 and through the receiving equipment 350 to cause the release of relay 361. The release of relay 361 thereby closes a circuit for relay 335 from battery, winding of relay 335, inner right-hand armature and front contact of relay 323 to ground at the make-before-break contacts of relay 361, causing the energization of this relay. This impulse is very short, as the operation of relay 224 5 opens the obvious energizing circuit for the slow-to-release relay 225 which in releasing closes an obvious circuit for the slow-to-release relay 218 which, in attracting its armatures, breaks the connection from the 1000 10 cycle source to the toll line at its left-hand armatures and back contacts. The duration of the impulse is therefore determined by the operating characteristics of relays 225 and 218. The operation of relay 218 also opens 15 at its right-hand armature and back contact, the locking circuit for relay 216 which, upon releasing, opens the locking circuit for relay 203. The release of relay 203 opens the energizing circuit for relay 224 which, in re- 20 leasing, disconnects the 1000 cycle source and causes the energization of relay 225 which in turn releases relay 218. When the impulse, therefore, ceases relay 324 is energized in series with relay 335 from battery, 25 through the winding of relay 335, winding of relay 324, left-hand armature and front contact of relay 335, left-hand armature and front contact of relay 323 to ground. The operation of relay 324 opens the locking 30 circuit for relays 323, 322 and 327 which relays all release. The release of relay 322 opens the circuit for relay 303 which, in re- 35 leasing, disconnects the busy signals 304 and 305. Relay 322, also opens at its outer right- 40 hand armature and front contact the lead 450 to ground for relay 408 which, after an interval, releases and opens the energizing circuit for relay 411. Relay 411, in retracting its outer left-hand armature, opens the 45 locking circuit for relay 414 which relay thereupon releases. At its inner right-hand armature, relay 411 disconnects ground from the windings of relays 407 and 471 whereupon these relays release. Relay 471, in re- 50 leasing, opens the normal energizing circuit for relay 499. The restoration of the automatic equipment now takes place in the manner well known in the art.

If, in the course of completion of the connection by the automatic exchange equipment all trunks for extending the connection are found busy, intermittent ground is connected to the terminal 429, from an interrupter such as 483 or any other suitable 55 means, at a certain rate, for example, 60 interruptions per minute. The first impulse to ground will operate relay 428 and the following ground operate relay 427 which thereafter will be interrupted at the corresponding rate to alternately close and open

the circuit for relay 326. This relay will consequently alternately connect and disconnect the source of 700 cycles interrupted at a 40 cycle rate to the toll line 220 and the lamp 25 will therefore be intermittently lighted at 60 interruptions per minute in a manner which is believed to be obvious. The flashing of this lamp indicates to the operator that all trunks are busy.

In the same manner if the called subscriber is found busy, ground will be connected to the terminal 429 at a different rate, such as will produce, for example, 120 impulses per minute from an interrupter such as 484 and the flashing of the lamp at this rate will indicate to the operator that the wanted subscriber's line is busy.

It should also be noted that lamp 25 may be flashed by the called subscriber at the rate at which his switchhook is moved up and down during the talking period. Relay 326 is operated when the switchhook is down and released when the switchhook is up.

If the operator at 100 desires to rering the called subscriber after he has replaced his receiver on the switchhook, she operates the ringing key 34 and the circuits function in exactly the same manner as when the wanted subscriber was first called that is relay 358 is released by the transmission of a current impulse from the 1000 cycle source, interrupted at the 20 cycle rate, and ground is thereby connected to the circuit for relay 499. The operation of relay 499 causes the application of ringing current from the source 492 through the established connection to resignal the wanted subscriber.

In case an automatic call extended from the automatic equipment is not intended for a subscriber, such as the one connected at 410, but for a subscriber that may be reached through the medium of another toll line, i. e. if a terminal bank, for example, the one represented by terminals 510, is reached by the brushes of the switch 511 and these terminals are connected to a toll line leading to another distant exchange and a subscriber in another exchange is the one desired, the automatic equipment at Fig. 4 will then merely serve for a so-called through connection. The equipments associated with this second toll line may be identical with that shown in Figs. 2 and 3 which may also serve for a through connection and would in that case be reached from a switch such as 275 making contact with terminals 276 of this toll line.

The operator at 100 will, in the case of a through connection not only dial a number that will bring the connection up to the terminals 510, but also an additional number for the desired subscriber in the second automatic exchange. The first func-

tion after the connection has been extended to terminals 510 in response to the first number, will then be the transmission over the second toll line for a short period of current from the 1000 cycle alternating current source interrupted at a 40 cycle rate as has hereinbefore been described at the operation of relay 331. This short application of current conditions the second distant exchange for receiving impulses from the operator at 100 representing the second number and it can be seen that as previously described when relay 332 operated the talking leads 455 and 456 will be extended to the toll line 220 at the upper and lower make-before-break contacts of relay 322. Leads 455 and 456 are then also, of course, connected over the second toll line to a second distant exchange upon receipt of a signal indication from the distant toll line equipment to indicate that the second number may be sent in the same manner as hereinbefore described in connection with the extension of a call to an automatic subscriber through the equipment at 300 and Fig. 4. The operator at 100 may now therefore, proceed in dialing the second number and the procedure will be the same as has already been described in connection with the extension of a call to the subscriber at 410. It should be stated that a relay similar to relay 222 is operated to disconnect the corresponding outgoing toll line equipment such as that shown at 200 from the second toll line. No further description need to be made as the following functions are exactly the same at the second distant exchange as has been previously described in connection with a call over the toll line 220. It is, therefore, seen that the toll line equipment as arranged in accordance with this invention may be utilized for through automatic connections as well as terminating automatic, terminating manual or through manual connections.

It now only remains to consider one more type of connections that may be extended by the use of this toll line equipment, namely a call intended for what is commonly known as an "out-delayed" operator, i. e., an operator having equipment arranged in a manner similar to the operator at 310 only that this operator is reached by having the operator at 100 dial a certain number or special code. In this case the operator at 100 proceeds in the same manner as when dialing for an automatic subscriber such as the one located at 410 only instead of reaching subscribers' line terminals she will be connected to terminals such as 515, connected directly to a ground and battery. This battery and ground is transmitted back over the line and will cause the operation of relay 516. Relay 516 in operating causes ground to be connected to lead 457 resulting in the operation of relays 325 and 341 over the following circuit: battery, left-hand winding of relay 325, lead 457 to ground at relay 516 for the energization of relay 335 and battery to the left-hand winding of relay 341, lead 457 to the ground at relay 516 for the energization of relay 341. Relay 341 provides a locking circuit for itself from battery, through the right-hand winding of this relay and its right-hand armature and front contact to ground at the outer left-hand armature and back contact of relay 342. This relay 341 at its left-hand armature and front contact closes an obvious circuit for the signal 343 which is thereby operated and indicates to the "out-delayed" operator that a connection is desired by the line associated with jack 344. Relay 325 provides a locking circuit for itself from battery, through its right-hand winding and inner right-hand armature and front contact to ground at the armature and back contact of relay 324. This relay 325 also prepares a locking circuit for relay 345, the purpose of which will be hereinafter described and at its outer left-hand armature and back contact removes the ground connection at relay 362 for lead 450 which causes the automatic equipment in Fig. 4 to be released to normal as hereinbefore described. When the "out-delayed" operator in answer to the lighting of lamp 343 inserts the plug of her cord circuit into jack 344, relay 342 is operated in the well known manner and the operation of this relay opens the locking circuit for relay 341 which is thereby released and causes the lamp 343 to be extinguished. Relay 342 in operating also closes an obvious circuit for relay 345 which now operates and locks to the ground at relay 324 over its inner left-hand armature and front contact and outer right-hand armature and back contact of relay 325. Relay 342 also disconnects the tip and ring leads to jack 314 from the line, whereas relay 345 causes the operation of relay 303 over an obvious circuit. The operation of relay 303 causes the operation of busy signals 304 and 305 as hereinbefore described. The connection between the operator at 100 and the "out-delayed" operator is now completed and conversation may take place.

It should be noted that in the event the "out-delayed" operator is used in through-connection the operator at 100 may send supervisory signals to this operator's cord circuit by virtue of the operation of relay 303 or through the connection completed at the inner left-hand armature and front contact of relay 325 by operations as hereinbefore described that will result in the release of relay 358, that is, relay 340 will be operated over a circuit as follows: battery, winding of relay 340, inner left-hand armature and front contact of relay 325, outer

right-hand armature and front contact of relay 323 to ground at relay 358 or from battery at relay 340 through the right-hand armature and front contact of relay 330 to ground at relay 358. The operation of relay 340 as hereinbefore described, connected current from the 20 cycle source and ground to the tip and ring leads connected through jack 344 to cause the supervisory lamp in the operator's cord circuit at 311 to light.

In case the "out-delayed" operator desires to recall the operator at 100 she may do so by moving her plug in and out of jack 344, thus causing the momentary release of relay 342 which will then complete a circuit for relay 326 from battery, winding of relay 326, left-hand armature and front contact of relay 345, inner left-hand armature and back contact of relay 342 to ground. The operation of relay 326 will then, as hereinbefore described, connect current from the 700 cycle source, interrupted at the 40 cycle rate and cause the flashing of lamp 25 at 100. If the "out-delayed" operator desires to break the connection she removes her plug from jack 344. This causes lamp 25 to be maintained lighted to serve as a designation for the operator at 100 to disconnect which she proceeds to do as hereinbefore described.

30 What is claimed is:

1. In a telephone system the combination of a toll line with means at one end thereof for transmitting over said toll line impulses of a high frequency alternating current at certain intervals, signaling means at the opposite end of said toll line responsive only to said alternating current impulses received at said intervals, means at the opposite end for transmitting over said toll line impulses of a high frequency alternating current of another frequency at certain intervals, and signaling means at the originating end of said toll line responsive only to said other alternating current impulses received at said intervals.

2. In a telephone system the combination of a toll line with means at one end thereof for transmitting over said toll line impulses of a high frequency alternating current applied at certain intervals and operative in response to the reception at said means of an impulse of low frequency alternating current, signalling means at the opposite end of said toll line responsive to said alternating current impulses, means at the opposite end for transmitting over said toll line impulses of a high frequency alternating current of another frequency applied at certain intervals and operative in response to the reception at said means of an impulse of low frequency alternating current, and signaling means at the originating end responsive to said other alternating currents.

3. In a signaling system, a source of high frequency alternating current of constant

amplitude, a transmission line, independent means for producing and applying to said line undamped impulses of alternating current from said source periodically at one rate, a second independent means for producing and applying to said line undamped impulses of alternating current from said source periodically at another rate, and means connected to said line selectively responsive to said undamped current impulses when periodically applied at said different rates.

4. In a telephone system the combination of a toll line with means for transmitting high frequency alternating currents applied at a certain rate from one end of said toll line, automatic switches at the opposite end of said toll line, means for associating said switches with said toll line actuated by said applied alternating currents, means for thereafter transmitting high frequency alternating currents applied at a different rate to said toll line, and means for controlling the switches in accordance with said high frequency alternating current impulses applied at said second rate.

5. In a telephone system the combination of a toll line with a dialing circuit, means for associating said dialing circuit with any one of said toll lines, means in said dialing circuit for transmitting over a toll line connected therewith high frequency alternating currents applied at a certain rate for a short period when said toll line is associated with the dialing circuit, automatic switches at the opposite end of said toll line, means associated with the opposite end of the toll line actuated by said momentarily applied alternating currents for associating said switches with said toll line, means in said dialing circuit for thereafter transmitting dialing impulses over the toll line said dialing impulses consisting of high frequency alternating currents, and means for controlling the switches in accordance with said dialing impulses.

6. In a telephone system the combination of a toll line with a cord circuit, a dialing circuit adapted to be connected to the cord circuit, a signal in said cord circuit operated when the dialing circuit is connected to the cord circuit, means in said dialing for connecting a momentary impulse of battery and ground to the toll line when the dialing circuit is connected to the cord circuit, means in the toll line and the cord circuit actuated by said battery and ground impulse to disable said signal in the cord circuit, means in said dialing circuit for thereafter transmitting high frequency alternating currents applied at a certain rate for a short period over the toll line to the opposite end of the same, automatic switches, means at the opposite end controlled by said momentarily applied alternating currents for associating said

switches with said toll line, and means in said dialing circuit for thereafter transmitting high frequency alternating currents applied at dialing rate for controlling said 5 switches in accordance therewith.

7. In a telephone system, the combination of a toll line, a cord circuit, a busy signal associated with the toll line, a signal associated with the cord circuit, means for operating the busy signal when the cord circuit is connected to the toll line, a dialing circuit adapted to be connected to the cord circuit, means for operating the cord circuit signal when the dialing circuit is connected to the cord circuit, means associated with the dialing circuit for applying a momentary direct current impulse to the cord circuit for transmission over the toll line, means associated with the dialing circuit 10 for applying, after the said momentary impulse, high frequency alternating current periodically at one rate for a short interval, means associated with the dialing circuit for thereafter applying high frequency alternating current periodically at a different rate, means associated with the cord circuit and toll line and actuated by the applied momentary impulse for disabling the cord circuit signal, and means connected to the 15 toll line selectively responsive to the high frequency alternating current when periodically applied at the said different rates.

8. In a telephone system, a source of high frequency alternating current, a transmission line, means for applying alternating current to said line periodically at one rate, means for applying said alternating current to said line periodically at a different rate, automatic switching mechanism, a 20 finder switch associated with said line, means for operating said finder switch to connect the line to the automatic switching mechanism responsive to said current applied at the first mentioned rate, and means 25 for controlling said automatic switching mechanism in response to said current applied at the second mentioned rate.

9. In a telephone system, a source of high frequency alternating current, a transmission line, means for applying alternating current to said line periodically at one rate, means for applying said alternating current to said line periodically at a different rate, automatic switching mechanism, a 30 finder switch associated with said line, means for operating said finder switch to connect the line to the automatic switching mechanism responsive to said current applied at the first mentioned rate, and means 35 for controlling said automatic switching mechanism in response to said current applied at the second mentioned rate, and means 40 for sending a signal for the release of said automatic switching mechanism and the finder switch actuated by the second op-

eration of the means for applying said current periodically at the first mentioned rate.

10. In a telephone system, a source of high frequency alternating current, a transmission line; means for applying said current to said line periodically at one rate, an impulse sender, means for applying said current to said line in pulses in accordance with the operation of the sender, subscribers' lines, automatic switching mechanism 70 having access to said subscribers' lines, a finder switch associated with said transmission line, means for operating said finder switch to connect the transmission line with the automatic switching mechanism responsive to said current applied at the first mentioned rate, a signaling means, a second source of high frequency alternating current of a different frequency, means for applying said second current to said line periodically at a certain rate when the automatic switching mechanism has been connected to the transmission line, means responsive to said applied second mentioned current for actuating said signal, means for 80 controlling said automatic switching mechanism in response to dial impulses to cause said mechanism to connect the transmission line with a subscriber's line corresponding to the number represented by the dial 85 pulses, means for disabling said signal during the operation of the impulse sender, means for removing the applied second mentioned current from the transmission line when all impulses from the sender have 90 been received to prepare for the operation of the signal, means for again operating the signal by the application of said second mentioned current to the transmission line if the wanted subscriber's line is idle, means 95 for disabling the signal when the subscriber answers in response to a second removal of the second mentioned current from the transmission line, and means for again operating the signal as a release when the subscriber hangs up in response to the application of the second mentioned current a 100 third time to the transmission line.

11. In a telephone system, a source of high frequency alternating current, a toll 115 line terminating in means for extending the line both automatically and manually, means for applying said alternating current to said line periodically at one rate, means for applying said alternating current periodically at a different rate, a busy signal associated with the manual extension means, and means responsive to current applied at the second mentioned rate to actuate said automatic extension means to disconnect the manual extension means from said line and actuate the busy signal thereat.

12. In a telephone system, a source of high frequency alternating current, a toll line terminating in means for extending the line 120

- both automatically and manually, means for applying said alternating current to said line periodically at one rate, means for applying said alternating current periodically at a different rate, a busy signal associated with the manual extension means, means responsive to current applied at one of said rates to disassociate said manual extension means to actuate the busy signal thereof and to prepare the automatic extension means for the reception of current applied at the second mentioned rate, and means responsive to current applied at said second mentioned rate to extend said line automatically.
13. In a telephone system, a source of high frequency alternating current, a toll line terminating in means for extending the line both automatically and manually, means for applying said current to said line periodically at one rate at a second rate and at a third rate, signals associated with the manual extension means, means responsive when said current is supplied at the first rate to operate said signals and when said current is applied at said second and third rates to actuate said automatic extension means, disconnect the manual extension means and to actuate some of said signals.
14. In a signaling system, a source of high frequency alternating current, a transmission line terminating in means for extending the line both automatically and manually, means for applying said current to said line periodically at one rate at a second rate and at a third rate, signals associated with said line at the manual extension means, means connected with said line responsive to said current when applied at one rate to operate said signals for the extension of the line manually, means connected to said line selectively responsive to said current when applied at said second and third rates to extend the line automatically and responsive to said current when applied at said second rate to disconnect the manual extension means and operate certain of said signals thereof.
15. In a signaling system, a transmission line terminating at one end in means for extending the line manually and at the opposite end in means for extending the line both automatically and manually, a source of high frequency alternating current of one frequency at one end of said line, a source of high frequency alternating current of another frequency at the opposite end of said line, means for applying current from one of said sources periodically to the line at three different rates, and means for applying current from the other of said sources periodically to the line at two different rates, and means responsive when the current of the first frequency applied at two of said three rates is applied in one direction to prepare and selectively extend the line automatically and when current of the same frequency is applied in the same direction at the other of said three rates to prepare the line for extension manually, means responsive when the current of the other frequency is applied at one of said two rates in the other direction to prepare the line for extension manually and when the same current is applied at the other of said two rates in the same direction to cause supervisory signals to be transmitted over the manual extension.
16. In a telephone system, a source of high frequency alternating current, a transmission line, means for applying said current to said line at two different rates, automatic switching mechanism, a second transmission line, means responsive to the application of said current at said rates for controlling said automatic switching mechanism to extend a connection from said first mentioned transmission line to said second mentioned transmission line, a second source of high frequency alternating current, a second automatic switching mechanism, means for applying current from said second source periodically at one rate over the second transmission line through the extension prepared by the first mentioned automatic switching mechanism, and means at the distant end of said second transmission line responsive to said current applied from said second source and to current from said first mentioned source applied at one of said rates for the control of said second automatic switching mechanism to extend the connection beyond.
17. In a signaling system, a transmission line terminating at one end in means for extending the line both automatically and manually, a source of high frequency alternating current, automatic switching mechanism, a station, means for applying current from said source at two different rates to control said automatic switching mechanism to extend a connection automatically to said station, a signal associated with the manual extension means, means actuated when said station is reached for releasing said automatic switching mechanism and actuating said signal at the manual extension means.
18. In a signaling system, a transmission line terminating at one end in means for extending the line both automatically and manually, a source of high frequency alternating current, automatic switching mechanism, a station, means for applying current from said source at two different rates to control said automatic switching mechanism to extend a connection to said station, a signal at the opposite end of said transmission line, signals associated with the manual extension means, means actuated when said station is reached for releasing

said automatic switching mechanism and actuating the signals at the manual extension means, means for seizing said manual extension means and actuating said means to disable one of the signals associated therewith, a second source of high frequency alternating current, means for applying current from said second source at a certain rate actuated when said manual extension means

is released from the seizing means therefor, 10 and means for actuating the signal at the opposite end of the transmission line when said second current is applied to the transmission line.

In witness whereof, I hereunto subscribe 15 my name this 19th day of June A. D., 1924.

PAUL B. MURPHY.
